UNITED STATES PATENT OFFICE.

HARRY RANDOLPH VAN DEVENTER, OF SUMTER, SOUTH CAROLINA.

PORTABLE ELECTRIC LIGHT.

1,189,755.

Specification of Letters Patent.

Patented July 4, 1916.

Application filed May 17, 1915. Serial No. 28,780.

To all whom it may concern:

Be it known that I, HARRY RANDOLPH VAN DEVENTER, a citizen of the United States, residing at Sumter, county of Sumter, State of South Carolina, have invented certain new and useful Improvements in Portable Electric Lights, of which the following is a specification, reference being had therein to the accompanying drawing.

My invention relates to portable electric lights and has for its object the production of a self-contained unit in which shall be combined a motor, a generator, a lamp and a control device, without any battery. In order to attain my object I mount a magneto generator of standard type upon a suitable base, mount a mechanically driven train of gears and a lamp upon the magneto, and inclose the whole within a pressed metal casing provided with a bull's-eye over the lamp on one side and a button for stopping and starting the clock-work on the other side.

My invention is illustrated in the accompanying drawing in which—

Figure 1 is a vertical longitudinal sectional view of my machine, showing the armature and connected parts in full lines. Fig. 2 is an end view with the casing partly broken away, showing the side plate, lamp, and rotor bearing. Fig. 3 is an opposite end view showing the spring motor.

Referring to the drawings, I preferably employ a magneto of standard commercial type, that is to say with two or more horse-shoe magnets having their polar ends provided with shoes having cylindrical opposing faces, between which a rotor revolves, and in its revolutions shifts the magnetic flux through the turns of a generating winding, which produces the desired current. In the present case, I have chosen to illustrate a magneto with an armature 6, having its winding grounded at one end as shown at 7, and the free end 8 connected to a collector ring 9 on which rests the brush 10, secured to a plate 11. The stem of the brush holder passes through the plate, from which it is insulated, and upon its upper end carries a spring 10^a, which is bent sharply upward with a set to the left, whereby it serves directly as one terminal of the lamp 12.

The armature shaft 1 is journaled in bearings formed in side plates 13 and 13^a, and has one end projecting at 1^a, to receive and carry the gear wheel 2, which is connected through the train of gears 2^a, 2^b, etc., to a

master gear on the spring drum 2^d. The spring in this drum or on the main arbre may be single, double, triple, or manifold, according to the length of time the lamp is to burn without rewinding. I do not herein describe the motor in detail because it is of a type which is well known, and specific differences will sufficiently appear from the illustration, the statement of operation, and the claims herein.

The side plate 13 carries a threaded socket which may be formed directly in the plate, for the base of the lamp 12, the circuit from this socket being completed through the metal side plate 13 to the shaft 1 of the armature and so to the winding 6 thereon. In other words, one side of the lamp is grounded on the frame, and the other side is directly connected through the lamp base and the spring 10^a to the brush 10, the collector ring 9 and the armature winding 8. This construction is not only extremely efficient because of the small number of joints and connections between the generator and the translating device, but it is also cheap and easy to make.

The field magnets 18, the upper portion of which is shown in section in Fig. 1, have their poles resting upon a base 19, which also forms the base for the entire lamp unit. The structure may be secured to its base in any suitable manner, but I have shown it as secured through the casing 20, which is fastened to the base by screws 21 or in any other suitable manner, and fits tightly over the crown of the field magnets, being shaped as shown in Figs. 1 and 3, so as to maintain the same against lateral as well as vertical displacement. The casing is provided with a handle 15 which may be secured by riveting as shown, and on one side carries a bull's-eye 16 which when the parts are assembled comes into position over the lamp 12, and on the other side carries a pin or button 5 which slides in and out, and when it comes into the path of the gear 2^a, it stops the train and the generator. By pulling the button out, after winding up the spring through a suitable key 4 on the spring arbre 3, the train will start to drive the magneto and the lamp will be lighted.

Having thus described my invention, what I claim and desire to secure by Letters Patent is:—

1. A self-contained lighting unit comprising the following instrumentalities: a base,

- a magneto generator mounted on said base having field magnets, a rotor, and generating windings, a train of spring driven gears connected to the rotor shaft on one side of the magneto, a lamp mounted on the other side of the magneto, circuit connections from said lamp to the generating windings, and a continuous metal casing surrounding the entire unit and secured to the base, said casing having an opening opposite the lamp, and a bull's-eye secured to the casing over said opening.
2. A self-contained lighting unit comprising the following instrumentalities: a base, a magneto generator mounted on said base having field magnets, a rotor, and generating windings, a train of spring driven gears connected to the rotor shaft on one side of the magneto, a lamp mounted on the other side of the magneto, circuit connections from said lamp to the generating windings, and a continuous metal casing surrounding the entire unit and secured to the base, said casing having an opening opposite one of the gears in the motor train, and means

fitted in said opening for stopping and starting the motor train, and thereby stopping and starting the operation of the generator and the illumination of the lamp.

3. A self-contained lighting unit comprising the following instrumentalities; a base, a magneto generator mounted on said base having field magnets, a rotor, and generating windings, a train of spring driven gears connected to the rotor shaft on one side of the magneto, a lamp mounted on the other side of the magneto, circuit connections from said lamp to the generating windings, and a continuous metal casing surrounding the entire unit and secured to the base, said casing having an opening opposite one of the gears of the motor train, and means fitted in said opening to engage said gear for the purpose of stopping the train, said means projecting outside the casing for manual manipulation, together with means also projecting through the casing for winding the spring motor.

In testimony whereof I affix my signature.

HARRY RANDOLPH VAN DEVENTER.
